(57) **CLAIM**

The ornamental design for a dipping tape as shown and described.

DESCRIPTION

FIG. 1 is a front isometric view of a dipping tape in a rolled state;

FIG. 2 is a rear isometric view of the dipping tape in the rolled state shown in FIG. 1;

FIG. 3 is a front view of the dipping tape in the rolled state shown in FIG. 1;

FIG. 4 is a rear view of the dipping tape in the rolled state shown in FIG. 1;

FIG. 5 is a side view of the dipping tape in the rolled state shown in FIG. 1;

FIG. 6 is a top view of the dipping tape shown in FIG. 1 in a straight state;

FIG. 7 is a bottom view of the dipping tape in the straight state shown in FIG. 6;

FIG. 8 is a front view of the dipping tape in the straight state shown in FIG. 6; and,

FIG. 9 is a rear view of the dipping tape in the straight state shown in FIG. 6.

The dipping tape is shown with symbolic break lines in its length to indicate indefinite length. The symbolic break lines are represented by broken lines. The appearance of any portion of the dipping tape between the break lines forms no part of the claimed design.

1 Claim, 5 Drawing Sheets
